UNITED STATES PATENT OFFICE.

ADOLF HUBER, OF HARTFORD, CONNECTICUT, ASSIGNOR OF ONE-THIRD TO ANTHONY M. JACOBS, OF HARTFORD, CONNECTICUT.

LOCK

No. 884,586.

Specification of Letters Patent. Patented April 14, 1908.

Application filed August 30, 1907. Serial No. 890,755.

To all whom it may concern:

Be it known that I, ADOLF HUBER, a citizen of Austria, residing at Hartford, in the county of Hartford and State of Connecticut, have invented a new and useful Lock, of which the following is a specification.

This invention relates to an improvement in tumbler locks and while the embodiment of the invention is illustrated and described herein as designed in the form of a trunk or chest lock, the invention is not limited to such a type of lock for by simply changing the form of the casing it can be adapted for use as a door, desk or cabinet lock.

15 The object of the invention is to provide a lock which when closed exposes no means by which it can be opened and when the means for opening it are exposed requires peculiar manipulation before the key will engage and 20 move the bolt, and then requires a particular number of turns of the key before the bolt is shot sufficiently to release the hasp or other part which the bolt engages for locking.

The trunk lock shown has a keyhole concealed beneath a lid which has no apparent means by which it can be opened but which instantly springs open when the plate or a trimming of the plate is pushed so as to release a catch which holds the keyhole lid 30 closed. The key when inserted in the keyhole that is exposed by the springing open of the lid, turns around idly until after the key-pintle is pressed inwardly by any means so as to release a tumbler that is carried by the bolt. 35 and with which tumbler the bit of the key must engage and move the bolt into such position that the subsequent turns of the key will lift the locking tumbler and shoot the bolt. When the bolt is to be locked the key 40 is given one turn to shoot the bolt so that it will engage the hasp or other locking part and then given a second turn to further shoot the bolt and finally a third turn which lifts the tumbler carried by the bolt until it is engaged by a spring pin connected with the key-pintle, which catch must be released from the bolt tumbler before the key can again move the bolt in either direction. 45 After the key is removed from the lock the lid is closed over the keyhole until the catch connected with the plate trimming engages and holds it fast.

Figure 1 of the accompanying drawings shows a side view of a lock with the parts closed and fully locked. Fig. 2 is a similar

view with the hasp removed and the lid opened so as to expose the keyhole. Fig. 3 shows a rear view of the lock. Fig. 4 shows a rear view of the locking mechanism with the parts in the positions occupied when 60 locked. Fig. 5 is a similar view with the parts in the positions occupied after the key-pintle has been pressed so as to release the bolt-throwing tumbler. Fig. 6 is a sectional view taken on the plane indicated by the dotted line x—x on Fig. 3. Fig. 7 is a view of the bolt. Fig. 8 is a view of the bolt tumbler. And Fig. 9 is a view of the locking tumbler.

The lock is shown in the views as mounted 70 on the back of a face plate 1 which is adapted to be secured to the face of a trunk, chest or other part. This form of lock has a hasp 2 that is designed to be fastened to the lid or other part that is to be lifted. The hasp has 75 a common socket or loop which is adapted to project through the usual hole in the face plate into position to be engaged by the bolt on the back of the face plate.

Around the keyhole 3 is a low wall or rib 80 4 and pivoted to this is a cover 5 which when open exposes the keyhole and when closed fits tightly within the wall and conceals the keyhole. On the back of this lid is a spring 6 which is compressed when the lid is closed 85 and which throws the lid open when the catch pin 7 that projects from the back of the lid through the opening 8 in the face plate is released from the spring bar 9 that is mounted on the back of the face plate. 90 One end of this spring bar is connected by a pin 11 with one of the trimmings 12 on the corner of the face plate. The spring of this bar normally holds it in such position that it will engage the pin 7 on the back of the 95 lid. When the trimming is pushed downwardly the bar is moved from the pin so that the spring will throw the lid open. When the lid is closed there is no apparent means connected with it or on the face of the plate 100 by which it can be opened.

The bolt 13 is movably held in place by the strap 14 and the back plate 15. On one edge of the bolt is a locking shoulder 16 and a locking shoulder 17. These shoulders are 105 adapted to be engaged by the hooked end of the locking tumbler 18 which has an arm 19 that extends between the bolt and the face plate into position to be lifted by the bit of the key when the key is turned. When the 110

bit of the key lifts the arm and locking tumbler the bolt is released so that it can be moved. There can, of course, be as many of these locking tumblers as is desired to add 5 to the security of the lock. A spring 20 is arranged to press the locking tumbler down so that its hooked end will engage the locking shoulders of the bolt.

Pivoted on the back of the bolt and movable with it is a tumbler 21. This tumbler is normally pressed downwardly by a spring 22. The bolt tumbler has a shoulder 23 that coincides with a shoulder on the bolt and which is engaged by the bit of the key 10 for moving the bolt one step in its locking movement and it has a shoulder 24 which coincides with a shoulder on the bolt and which is engaged by the bit of the key on its second turn for moving the bolt 15 second step of its locking movement. The tumbler has an arm 25 that extends below the bolt and that on the third turn of the key is engaged by the bit and is lifted to the position shown in Fig. 4 in which position 20 it is engaged and held by a stud 26 that is mounted on a spring plate 27 fastened to the back face of the back plate. When this tumbler is held lifted in this manner the bit of the key will turn around without engaging 25 the tumbler or any shoulder on the bolt.

Fastened to the back face of the back plate is a spring plate 28 that extends beneath the spring plate 27. Fastened to this spring plate 28 is the key-pintle 29 that 30 projects forwardly into the keyhole and upon which the key turns. When the key-pintle is pressed backwardly with sufficient force the spring plate 28 pushes backwardly the spring plate 27 and withdraws the catch 35 stud 26 from engagement with the tumbler 21, allowing that tumbler to be thrown down into the position shown in Fig. 5. When the tumbler is in this position the first backward turn of the key engages the shoulder 30 and

withdraws the bolt one step. The next turn 45 of the key will engage the shoulder 31 on the tumbler and a coinciding shoulder on the bolt and moves the bolt the next step.

It takes three turns of the key to fully lock the parts, the first turn throws the bolt and 50 bolt tumbler one step, the second turn throws the bolt and bolt tumbler the second step and the third turn lifts the bolt tumbler until it is engaged by the catch. As stated if the key is simply inserted in the keyhole it turns 55 idly until the pintle is pressed to release the bolt tumbler. When the key-pintle is pressed and the bolt tumbler is released the first turn of the key engages the bolt tumbler and draws back the bolt one step and the next turn 60 engages the bolt tumbler and the bolt and withdraws the bolt the second step.

The invention claimed is:—

A lock having a bolt with a shoulder adapted to be engaged by the bit of the key 65 for moving the bolt one step, a locking tumbler adapted to engage the bolt and to be disengaged from the bolt by the bit of the key, a tumbler mounted on the bolt and having a shoulder adapted to be engaged by the 70 key for moving the bolt one step and a part adapted to be engaged by the bit of the key and so lifted that the shoulder on the tumbler will be out of the path of the bit of the key, a catch adapted to engage and temporarily hold the bolt tumbler out of the path 75 of the key when the bolt tumbler is lifted by the bit of the key, a movable key pintle and a connection between the pintle and the catch whereby the movement of the pintle disengages the catch from the bolt tumbler and allows that tumbler to be dropped so that its shoulder lies in the path of the bit of the key, substantially as specified.

ADOLF HUBER.
